UNITED STATES PATENT OFFICE

RICHARD MARX, OF DETROIT, MICHIGAN.

RADIATING-DRUM.

1,178,662.

Specification of Letters Patent. Patented Apr. 11, 1916.

Application filed February 25, 1915. Serial No. 10,454.

To all whom it may concern:

Be it known that I, RICHARD MARX, a citizen of the United States of America, residing at Detroit, in the county of Wayne and State of Michigan, have invented certain new and useful Improvements in Radiating-Drums, of which the following is a specification, reference being had therein to the accompanying drawings.

10 This invention relates to a radiating drum, and the objects of my invention are to provide positive and reliable means, in a manner as hereinafter set forth, for baffling and retarding products of combustion, hot air and the heated gases, whereby heating units can be derived from the products of combustion before their final escape to an exhaust flue or chimney, and to provide a radiating drum with detachable baffles that 15 can be easily and quickly removed whereby the baffles and the interior of the drum can be cleansed of soot and other foreign matter that may accumulate therein.

Further objects of my invention are to 20 provide a radiating drum with a sinuous or tortuous path for products of combustion which are carried against the walls or periphery of the drum to heat the same, and to accomplish the above results by a simple, 25 durable and inexpensive chimney or flue drum that permits of a high degree of heat being obtained by a minimum expenditure of fuel.

The above are a few of the objects attained by the novel construction, combination and arrangement of parts hereinafter specifically described and then claimed, and reference will now be had to the drawings, wherein—

40 Figure 1 is a front elevation of the radiating drum; Fig. 2 is a plan of the same with the cover thereof removed; Fig. 3 is a perspective view of the drum partly broken away; Fig. 4 is a perspective view of the superimposed baffle; and Fig. 5 is a perspective view of a detached bottom baffle.

A radiating drum in accordance with this invention comprises a fixed circular head 1 carried by the lower end of a cylinder or cylindrical shell 2 which has the upper end thereof provided with a detachable circular head or cover 3. The heads 1 and 3 are provided with concentric openings for sleeves 4. These sleeves permit of the radiating drum 55 being easily and quickly installed in connec-

tion with a stove pipe or the exhaust conduit of a heating apparatus.

A side of the cylinder or cylindrical shell 2 has an opening normally closed by a hinged door 5. This door permits of easy 60 access being had to the interior of the cylinder for removing soot or other foreign matter.

Within the cylinder 2 and resting upon the head 1 are the legs 6 of a bottom baffle 7, said baffle being triangular in plan and in spaced relation to the header 1. Centrally of the bottom baffle 7 is a support 8 riveted or otherwise connected to the baffle. This support co-operates with other supports 9 70 in spacing and holding a plurality of superimposed baffles 10 within the cylinder 2. The baffles 10 are triangular in plan, similar to the bottom baffle 7 and in placing the baffles in position, the radiating portions of 75 one baffle are staggered relative to the radiating portions of other baffles, thereby providing a sinuous or tortuous passage from the bottom of the cylinder 2 to the top thereof. Products of combustion caused to 80 travel in the sinuous passage of the cylinder contact with the walls or periphery of the cylinder thus heating the same and air surrounding the cylinder.

All of the baffles can be easily and quickly 85 placed in position by simply removing the upper header or cover 3, and with the device in its entirety made of light and durable sheet metal, the entire device is thoroughly heated before the escape of products of 90 combustion or heated gases from the top of the drum.

I attach considerable importance to the simplicity of construction, as the drum can be manufactured at a comparatively small 95 cost, thus permitting of its installation in connection with a low grade of stove, whereby a maximum of amount of air can be heated at a minimum expenditure of fuel.

One embodiment of my invention has been 100 illustrated, but it is to be understood that the structural elements are susceptible to such variations and modifications as fall within the scope of the appended claim.

What I claim is:—

A radiating drum comprising a cylinder, heads carried by the ends thereof and provided with concentric openings, a flat bottom baffle having integral legs supported by one of said heads, superimposed flat baffles 110

above said bottom baffle, supports connecting said baffles centrally of said cylinder and all of said baffles being triangular in plan with radiating portions of one baffle staggered relative to radiating portions of other baffles to provide a tortuous passage throughout the length of said drum.

In testimony whereof I affix my signature in presence of two witnesses.

RICHARD MARX.
